(57) **CLAIM**

The ornamental design for a golf ball-shaped container, as shown and described.

DESCRIPTION

FIG. 1 is a front perspective view of the golf ball-shaped container of the present invention;

FIG. 2 is front view thereof;

FIG. 3 is a rear view thereof;

FIG. 4 is a left-side view thereof;

FIG. 5 is a right-side view thereof;

FIG. 6 is a bottom plan view thereof; and,

FIG. 7 is a top plan view thereof.

The broken lines define the bounds of the claimed design and form no part thereof.
